UNITED STATES PATENT OFFICE.

INGENUIN HECHENBLEIKNER, OF CHARLOTTE, NORTH CAROLINA, ASSIGNOR TO
CHEMICAL CONSTRUCTION COMPANY, OF CHARLOTTE, NORTH CAROLINA, A
CORPORATION OF NORTH CAROLINA.

EXHAUSTER.

1,308,756.

Specification of Letters Patent.

Patented July 8, 1919.

Application filed November 2, 1918. Serial No. 260,901.

To all whom it may concern:

Be it known that I, INGENUIN HECHENBLEIKNER, a citizen of the United States, residing at Charlotte, in the county of Mecklenburg and State of North Carolina, has invented certain new and useful Improvements in Exhausters, of which the following is a specification.

For exhausting or impelling acid fumes or other active gases by means of fan blowers or the like, the form and substance of the fan casings are a matter of considerable difficulty, the use of metal casings being prohibited or objectionable because of the corrosive action of the gases. Hence, masonry or earthenware casings are advisable and the object of the present invention is to provide a fan casing of this type, suitable for use with nitrous or other acid gases, and constructed in such manner that either one or two fans may be employed, controlling valves being provided to regulate or direct the flow of gas according to the amount desired or to the fan or fans employed.

25 The structure embodies a pair of fan chambers between which is an inlet or supply chamber with suitable valves therein controlling the flow therefrom to either or both of the fans; and valved outlet passages 30 are also provided leading to a common outlet chamber. The construction is characterized by the use of masonry or earthenware parts in the main.

In the accompanying drawings, Figure 1 is a section on the line 1—1 of Fig. 2, the valves being removed. Fig. 2 is a section on the line 2—2 of Fig. 1. Fig. 3 is a section on the line 3—3 of Fig. 1. Fig. 4 is a section on the line 4—4 of Fig. 1, and Fig. 5 is a section on the line 5—5 of Fig. 1.

The casing comprises a substantially rectangular structure indicated at 6, made of brick work or masonry, strengthened by outside tie rods 7. 8 is an inlet pipe at one end 45 of the structure and 29 is an outlet pipe at the opposite end. The inlet pipe 8 leads to the bottom of a supply or distributing chamber 9 which is located between a pair of fan chambers 10, with suitable partition walls 11 between. The fan chambers are arched or curved to conform to the shape of the rotary fan or blower used. The fans may be of any suitable type and are omitted because they form no part of the invention.

The top of the fan chambers is preferably 55 made of relatively large blocks 10^a which can be removed through the openings 10^b in the top of the masonry to permit access to the chambers, the openings being ordinarily closed by slabs 10^c. So-called chemical brick 60 will be employed for the masonry, and each side wall of the casing has an opening 10^e for the fan shaft of the respective fans, removable wedge blocks 10^d filling a space above the bearing blocks to permit removal 65 or insertion of the fan shaft.

Each fan chamber has a central inlet and a tangential outlet, the latter being indicated at 12. The inlets connect the intermediate supply or distributing chamber 9 with 70 the fan chambers 10, and each inlet consists of a stoneware elbow pipe or bell 13 which extends respectively through the walls 11, with their mouths presented upwardly in the intermediate chamber 9. These mouths 75 are belled, as indicated at 14, to form seats for the stoneware valves 15, each of which is connected to an operating rod 16 extending through the top of the casing. Any suitable means may be provided for operating the 80 rods to open or close the valves, and as shown especially in Fig. 1, the elbow pipes 13 are offset at their inner ends to bring the mouths in longitudinal alinement in the supply chamber. This saves space and material. The tangential outlets 12 from the bottom of the respective fan chambers lead to elbows 25 which open upwardly into an outlet chamber 26 at the end of the casing, the outlet pipe 29 communicating with this 90 chamber at the middle thereof. The mouths of the elbows 25 are belled and form seats for the earthenware valves 17, which are connected to rods 18, extending through the top of the chamber and operated by any suitable means, as by hand wheels 19. By-pass bends 20 and 21 are set in the bottom of the casing, connecting the chambers 9 and 10 and 9 and 26. These provide drainage from the chambers 10 and 26 to the chamber 9, the 100 bottom of which is sloped toward the inlet sufficiently to carry off condensation, which may be tapped off from the inlet pipe line in any suitable way.

In the operation of the exhauster, either 105 one or both fans may be used. When one is used, the appropriate valves 15 and 17 are opened and the other valves closed. The

gases then enter through the inlet 8 to the supply chamber 9 and elbow 13 to the eye of the fan and are forced out through the passages 12 and 25 to the chamber 26 and thence 5 to the outlet pipe 29. Ordinarily only one fan will be used, the other being held in reserve. In addition to distributing the gases to either fan, the chamber 9 serves as a condensing chamber to collect the condensation 10 which is sometimes considerable, from acid fumes, and the inlet elbows 13 are located above the floor of this chamber so that condensation is not conducted, in any considerable amount, to the fan chambers. As shown 15 in Fig. 5, the elbows 13 are supported at one end in the walls 11 and at the opposite end by the other wall 11, so that they are rigidly held in position with the valve seats perfectly level so that the valves will fit tightly. 20 A similar effective support is provided for the elbows 25 which are built solidly in the masonry as shown especially in Fig. 4.

I claim:

1. A fan casing having a fan chamber 25 therein and a supply and condensation chamber beside the fan chamber, an elbow pipe from the latter chamber to the former, the mouth of the pipe being located above the bottom of the supply chamber and presented 30 upwardly, and a valve controlling said mouth and having an operating rod extending through the wall of the casing.
2. A fan casing having a pair of opposite 35 fan chambers therein and a supply and condensation chamber between the fan chambers and separated by partition walls therefrom, and a pair of inlet elbow pipes from the latter chamber to the former chambers 40 respectively, the ends of said inlet pipes in the supply chamber having valve seats and

being supported at opposite sides by said partition walls, and valves coöperating with said seats.

3. A fan casing having a fan chamber and a supply chamber located beside each other 45 and separated by a wall, an elbow pipe connecting said chambers, the end of the pipe in the supply chamber being provided with a valve seat, and supported at opposite sides by the opposite side walls of said chamber, 50 and a valve coöperating with said seat.

4. A fan casing having a pair of fan chambers at opposite sides thereof, an intermediate supply chamber between said chambers, an outlet chamber extending across the 55 ends of said chambers, valved passages connecting the supply chamber to the respective fan chambers, and valved passages connecting the fan chambers to the outlet chamber.

5. A fan casing having supply and fan 60 chambers standing side by side therein, and an outlet chamber adjacent the ends thereof, and drainage pipes connecting the fan and outlet chambers to the supply chamber.

6. A fan casing having a fan chamber at each side thereof and an intermediate supply and condensation chamber between the fan chambers, an elbow pipe connecting the supply chamber to each fan chamber, said elbow pipes having mouths located in longitudinal alinement with each other in the supply chamber and supported at opposite sides by the opposite walls of said chamber, and valves coöperating with said mouths.

In testimony whereof, I affix my signature in presence of two witnesses.

INGENUIIN HECHENBLEIKNER.
